US00D710818S

(12) **United States Design Patent**
Ota

(10) **Patent No.:** **US D710,818 S**
(45) **Date of Patent:** **** Aug. 12, 2014**

(54) **VOICE RECORDING/REPRODUCING DEVICE**

D676,075 S * 2/2013 Ku D16/208
D688,226 S * 8/2013 Morisawa D14/167
D690,703 S * 10/2013 Welch et al. D14/440

(71) Applicant: **Olympus Imaging Corp.**, Tokyo (JP)

* cited by examiner

(72) Inventor: **Hiroyuki Ota**, Yokohama (JP)

Primary Examiner — Austin Murphy

(73) Assignee: **Olympus Imaging Corp.**, Tokyo (JP)

(74) *Attorney, Agent, or Firm* — Holtz Holtz Goodman & Chick PC

(**) Term: **14 Years**

(57) **CLAIM**

(21) Appl. No.: **29/482,986**

The ornamental design for a voice recording/reproducing device, as shown.

(22) Filed: **Feb. 24, 2014**

DESCRIPTION

(30) **Foreign Application Priority Data**

Nov. 6, 2013 (JP) 2013-025948

FIG. 1 is a rear, top and right side perspective view showing my new design;

(51) **LOC (10) Cl.** **14-01**

FIG. 2 is a front elevational view thereof;

(52) **U.S. Cl.**

FIG. 3 is a rear elevational view thereof;

USPC **D14/167**

FIG. 4 is a top plan view thereof;

(58) **Field of Classification Search**

FIG. 5 is a bottom plan view thereof;

USPC D14/167, 154, 168, 188, 496, 156, 160,

FIG. 6 is a right side elevational view thereof;

D14/161, 162, 163, 164, 165, 158, 203, 1,

FIG. 7 is a left side elevational view thereof;

D14/341, 346, 342, 345, 225, 226, 228, 227,

FIG. 8 is a right side elevational view showing a state where a part of a rear surface of a case thereof is erected and used as a stand;

D14/214; 455/351, 350; D19/60, 62;

FIG. 9 is a left side elevational view showing a state where a part of a rear surface of a case thereof is erected and used as a stand;

D21/330; 369/44.14, 44.32; 700/94

FIG. 10 is a rear, top and right side perspective view showing a state where a part of a rear surface of a case thereof is erected and used as a stand; and,

See application file for complete search history.

FIG. 11 is a bottom and right side perspective view showing a state where a part of a rear surface of a case thereof is erected and used as a stand.
